UNITED STATES PATENT OFFICE

HARVEY H. STONER, OF SPRINGFIELD, AND WILLIS D. STONER, OF DAYTON, OHIO

DESIGN FOR AN AERIAL SCOOTER

Application filed July 3, 1930. Serial No. 36,271. Term of patent 3½ years.

To all whom it may concern:

Be it known that we, HARVEY H. STONER, residing at Springfield, in the county of Clark and State of Ohio, and WILLIS D. STONER, residing at Dayton, in the county of Montgomery and State of Ohio, both citizens of the United States, have invented a new, original, and ornamental Design for Aerial Scooter, of which the following is a specification, reference being had to the accompanying drawing, forming a part thereof.

Fig. 1 is a side elevation and Fig. 2 is an end elevation of an aerial scooter showing our new design.

We claim:

The ornamental design for an aerial scooter as shown.

HARVEY H. STONER.
WILLIS D. STONER.
